UNITED STATES PATENT OFFICE.

EMIL FREDERICK KAISER, OF FRESNO, CALIFORNIA.

SHADE-ROLLER BRACKET.

SPECIFICATION forming part of Letters Patent No. 696,568, dated April 1, 1902.

Application filed April 18, 1901. Serial No. 56,404. (No model.)

To all whom it may concern:

Be it known that I, EMIL FREDERICK KAISER, a citizen of the United States, residing at Fresno, in the county of Fresno and State of California, have invented certain new and useful Improvements in Shade-Roller Brackets; and I do declare the following to be a full, clear, and exact description of the invention, such as will enable others skilled in the art to which it appertains to make and use the same.

The invention relates to shade-roller brackets; and the object of the invention is to improve the construction shown and described in Letters Patent No. 667,943, granted to me February 12, 1901, whereby the cost of manufacture is reduced to a minimum without impairing the efficiency of the device.

With this and other objects in view the invention consists of certain novel features of construction, combination, and arrangement of parts, which will be hereinafter more fully described, and particularly pointed out in the appended claim.

In the accompanying drawings, Figure 1 is a view of the upper corner of a window-frame, illustrating my invention. Fig. 2 is an end view of the device removed. Fig. 3 is a vertical sectional view. Fig. 4 is a rear view showing the position of the bracket-arm when supporting a shade-roller, the outer upper corner of said arm being shown engaged with one of the teeth of the rack-bar against outward movement; and Fig. 5 is a detail perspective view of the bracket-arm removed.

Referring to the drawings, 1 denotes the base-plate, provided with a longitudinal slot 2 and having its outer end offset, as shown at 3, and provided with offset ears 4, the ears 40 and end being provided with holes 5, through which screws or nails are adapted to be inserted to secure the base-plate in position and at the same time hold it spaced out a slight distance in advance of the window-frame, for a purpose hereinafter described. The upper wall 6 of the longitudinal slot 2 is in the form of a rack-bar, and the outer end of the plate at the point of deflection of its offset end is provided with a vertical slot or opening 7.

8 denotes a bracket having two arms 8^a and 8^b at right angles to one another, the apex of the angle being formed with oppositely-dis-

posed notches 9 and the outer end of the arm 8^a being formed with a reduced neck 10, which is provided with a T-shaped head 11, the length of which is greater than the breadth of the longitudinal slot 2, while the width of the neck 10 is less than that of the said slot 2. The arm 8^b of the bracket is provided with a convex pivot-hole 8^c on its inner side to receive the journal of the shade-roller. It is understood that one of these devices is secured to each of the upper corners of the window-frame in position to support the shade-roller in the usual manner. The bracket-arm 8^a is engaged with the base-plate by matching the notches of said arm with the vertical slot or opening 7 of the plate and then slipping the arm sidewise into the longitudinal slot 2 of said plate, with the rear wall of the notched portion 9 of the bracket engaging the rear face of the plate and the T-shaped head 11 engaging the forward face of the plate. The bracket is adjusted to suit the length of the shade-roller used and automatically locks 75 itself in adjusted position, for the weight of the shade-roller on the arm 8^a tends to tilt said arm axially slightly, since the width of the neck 10 is less than the width of the slot 2 in the base-plate, and this movement throws 80 the upper outer corner of the neck portion of said arm into one of the rack-teeth, as shown in Fig. 4.

From the foregoing description, taken in connection with the accompanying drawings, 85 the construction, mode of operation, and advantages of my invention will be readily understood without requiring a more extended explanation.

Various changes in the form, proportion, 90 and details of construction may be made within the scope of the invention without departing from the spirit or sacrificing any of the advantages thereof.

Having thus described my invention, what 95 I claim, and desire to secure by Letters Patent, is—

In a shade-roller bracket, the combination with the supporting-plate having an offset end and formed with a longitudinal slot and with 100 a vertical slot or opening at the outer end of the longitudinal slot and at the junction of the offset end, one wall of said slot being provided with a row of rack-teeth, of an angular

bracket, the apex of which is formed with notches and one arm of which is provided with a neck and with a T-shaped head, said neck being of less width than the width of the longitudinal slot whereby the bracket-arm is permitted to tilt axially and engage the rack-teeth aforesaid to lock the bracket-arm in longitudinal adjustment, substantially as set forth.

In testimony whereof I have hereunto set my hand in presence of two subscribing witnesses.

EMIL FREDERICK KAISER.
